BUBBLE CAP SECURING DEVICE

Bradford C. White, Lexington, Mass., assignor to
 Stone & Webster Engineering Corp., Boston,
 Mass., a corporation of Massachusetts

Application August 6, 1946, Serial No. 688,634

11 Claims. (Cl. 261—114)

1

This invention relates to bubble cap-riser units of fractionating tower bubble trays and relates more particularly to devices for removably securing the bubble caps in position over the risers.

A usual mode of installing and removably securing bubble caps in position over the vapor risers of bubble trays within a fractionating tower is to run the shank of a T bolt fastening device up through the bottom opening of the riser from the tray below. By thus operating from beneath the tray, accidental dropping of the T bolt through the riser of the tray being worked on to the tray below, is prevented. The head or crossbar of the T bolt is then either tack welded to the riser or is held up by means of a holding bar. Installation of the bubble cap then follows. However, this procedure requires two men to insert the bolts and install the bubble caps, and a man to do the tack welding.

One object of this invention is to overcome the disadvantages aforesaid through the provision of a new and useful bubble cap-riser unit that will enable the cap fastening device to be installed from above the bubble tray without possibility of its being dropped through the riser, that will enable the entire installation to be effected by one man, and requires no welding of the cap fastening device to the riser.

Another object of this invention is to provide in a bubble cap-riser unit for fractionating tower bubble trays, a new, useful and improved anchoring or holdown device for the bubble cap.

Another object of this invention is to provide a holdown device for removably securing or anchoring a bubble cap or like cap member in position over a vapor riser or like tubular member to be capped, that is self-centering in respect of the riser member when installed and will assume a normally upright position in the riser prior to application of the cap member.

Another object of this invention is to provide a holdown device for use with bubble caps which is cheaper to manufacture, more easily installed and may be more easily replaced in service.

Other and further objects of this invention will appear from the following description, the accompanying drawing and the appended claims.

In the accompanying drawing which forms part of the instant specification and is to be read in conjunction therewith and in which like numbers refer to like parts throughout the views thereof;

Figure 1 is a fragmentary view in vertical section of a portion of a bubble tray embodying this invention, the view depicting the installed relationship of a single riser in accordance with this

2

invention, its holdown device and bubble cap; and,

Figure 2 is a view in plan of the combination of Figure 1 with the bubble cap removed in order to show details of the holdown device.

In general and in accordance with this invention, a vapor riser is provided with a pair of diametrically opposed openings between its tray and the top of the riser. These openings may be 10 punch-drilled or punched to a jig and are of a size adequate to receive freely and loosely the respective ends of the head or cross-bar of the novel holdown or fastening device of this invention.

In accordance with this invention also, the 15 shank or stem of the holdown device is provided with a support member; that is, a pair of supporting arms extending laterally outwardly from the shank or stem of the holdown device in vertically spaced relation to the cross bar and preferably disposed at right angles, or substantially at right angles, to the shank and at opposite sides thereof. The support member is also of a length at least slightly in excess of the inside diameter of the vapor riser and is preferably of a length corresponding to the outside diameter of the vapor riser. Thus, the device cannot be dropped or passed through the vapor riser even when canted, but will be prevented from doing so by the support member engaging the top rim of the riser. Moreover, the spacing between the cross member and support member of the holdown is of a determined magnitude such that with the cross member seated in the openings in the walls of the vapor riser, the support member will rest upon the 25 upper rim of the vapor riser, thereby to support the holdown in a vertically upright position thus facilitating subsequent application of the bubble cap thereto. Preferably also, the support member is disposed at right angles to the cross bar and thus may offer a convenient handle for the 30 installer to grip in initially guiding the holdown device into position in the riser and the riser openings.

In accordance with the invention moreover, 35 the opposite ends of the cross bar are preferably provided with enlarged portions forming centralizing members disposed preferably on the top surface of the cross bar and of a magnitude, dimension and configuration to engage, or substantially engage, the outer periphery of the 40 riser when the cross bar is properly lodged in the riser wall openings, thereby automatically to locate the stem of the holdown centrally of the vapor riser. The free end of the holdown shank 45 is preferably threaded to receive a securing nut,

and, in accordance with conventional practice, is adapted to pass through a central opening in the bubble cap. The bubble cap is preferably supported on the rim of the vapor riser and is removably anchored in position over the vapor riser in the usual fashion as by the securing nut threadedly engaging the shank of the holddown device and frictionally engaging the bubble cap.

Referring now more particularly to the accompanying drawings, a vapor riser 1 of a bubble plate 2 is provided adjacent its top with a pair of corresponding preferably circular openings 3 located at diametrically opposite sides of the riser. A holddown member of cast, welded or stamped construction having the head or cross bar 4 and shank 5 is removably disposed in the riser with its cross bar ends lodged in the respective openings 3. Each end of the cross bar 4 is preferably equipped on the top surface with an enlarged portion forming a centralizing member 6 of a width preferably less than that of the cross bar 5. The respective centralizing members 6 extend inwardly from the ends of the cross bar a distance sufficient to ensure that in the installed position of the device they will substantially engage the outer periphery of the riser 1 thereby to locate the device centrally of the riser. Preferably also, the centralizing members are provided, respectively, with an inclined plane surface portion 7 which by engaging the riser 1 assists in centrally locating the holddown in the riser, that is, it has a self-centering function.

The openings 3 are suitably dimensioned to permit the free entry and withdrawal of the cross bar ends in the assembling and disassembling of the unit. The openings are preferably circular, but it is obvious that they may be of any other suitable configuration consistent with the attainment of the foregoing ends and objects.

A support member 10 extends laterally outwardly in opposite directions from the shank 5 and at right angles, or substantially right angles, to the shank and to the cross bar 4. In length, the support member 10 is suitably dimensioned so as to overlie at each end the top rim 11 of the riser 1 thereby to prevent passage of the holddown device through the riser should it be accidentally dropped as it is being installed or removed. Additionally, the support member is disposed a determined distance away from the cross bar 4 to rest upon the rim 11 when the cross bar 4 is seated in the openings 3 and thus serves to hold the device upright before the bubble cap 8 is applied.

The holddown shank 5 is of sufficient length to extend through the bubble cap 8 which is preferably provided with radial webs 9 by which the cap is supported on the rim 11. The bubble cap is centrally apertured as at 12 for the passage of the holddown shank and a threaded end portion 13 of the shank is adapted to be threadedly engaged by a nut 14 by which the bubble cap is normally held firmly in position over the riser with its mounting lugs 9 seated on the riser rim 11.

In order to disassemble the unit, the nut 14 is removed and the bubble cap 8 lifted off. The removal of the nut 14 will permit the holddown device to drop down to a position wherein the ends of the cross bar 4 will be seated on the bottom marginal walls of the openings 3 with the holddown in an upright position. In this position, the centralizing members 6 will clear the upper marginal rim of the openings 3 and the holddown may be moved laterally in either direction axially of the cross bar to disengage one or

the other of its ends from the corresponding opening 3. The holddown is then tilted sufficiently to permit its withdrawal from the other opening and from the riser. Installation is accomplished in the reverse order.

Thus, it will be observed that the objects of this invention have been accomplished. The installation and removal of the cap fastening device may be accomplished from above the tray without danger of the holddown being lost to the tray below; only one man is necessary for the entire operation; welding is entirely dispensed with, thus facilitating removal for replacement and repair; and cost is no greater than that of the more conventional types of fastening devices for the purpose; and, the ease of installation is markedly improved.

It will be understood that certain features and sub-combinations are of utility and may be employed without reference to other features and sub-combinations. This is contemplated by and is within the scope of the appended claims. It is further obvious that various changes may be made in details within the scope of the appended claims without departing from the spirit of this invention. It is therefore to be understood that this invention is not to be limited to the specific details shown and described.

Having thus described this invention, what is claimed is:

1. A bubble tray comprising a vapor riser having a pair of oppositely disposed wall openings; a holddown device having a cross member extending through said openings and having a shank extending lengthwise of said riser to beyond the top rim thereof, said device additionally having a support member extending laterally outwardly of said shank for supporting the holddown device in an upright position in said riser when said cross member is seated in said openings; a bubble cap supported in position over said riser; and, securing means co-acting with the shank of said holddown device and with said bubble cap for holding said bubble cap in said position.

2. The combination with a vapor riser and a bubble cap therefor of: a holddown device for said cap, said device having a shank and a cross bar extending at right angles to said shank through oppositely disposed openings in the wall portions of said riser, having a support member extending outwardly from said shank in opposite directions at substantially right angles thereto over the top rim of said riser for supporting the holddown device in an upright position in said riser when said cross bar is seated in said openings, said cross bar having enlarged portions at its ends for locating said shank substantially centrally of said riser; and means carried by said shank for securing said bubble cap in position over said riser.

3. The combination with a vapor riser and a bubble cap therefor of: a holddown device for removably securing said bubble cap in position over said riser, said device having a shank and a cross bar extending through oppositely disposed openings in the wall portions of said riser, said cross bar having inclined surface enlarged portions disposed at the top end portions of said cross bar in substantial engagement with the outer periphery of said vapor riser, and said device having also a support member spaced from said cross bar and extending in opposite directions from said shank at substantially right angles thereto and to said cross bar over the top

rim of said riser for supporting the holddown device in an upright position in said riser when said cross bar is seated in said openings.

4. A holddown device for removably securing a bubble cap on the end of a vapor riser comprising in integral relation an elongated head portion adapted to be disposed in the riser with its terminal portions in oppositely disposed openings in the wall of the riser; a shank portion at substantially right angles to said head portion having provision for receiving fastening means; and, a pair of supporting arms in a vertical plane at substantially right angles to said head portion, for supporting said shank portion in an upright position in the riser, said arms also being suitably spaced from said head portion along said shank portion to permit canting of said shank portion sufficient to effect insertion of said terminal portions in said openings as aforesaid and being of a length greater than the inside diameter of the riser with which it is adapted to be used, whereby said device may not be passed through the riser.

5. A holddown device according to claim 4 in which said head portion has enlarged end portions forming centralizing members at its opposite ends for centrally locating the device in the vapor riser when in use.

6. A holddown device according to claim 4 in which said shank portion has a threaded end.

7. A holddown device according to claim 4 in which said head portion has enlarged end portions each having an inclined surface and forming centralizing members at its opposite ends for centrally locating the device in the vapor riser when in use.

8. A holddown device according to claim 4 in which said supporting arms are carried by said shank portion and extend laterally outward therefrom at substantially right angles thereto and to said head portion.

9. A holddown device according to claim 4 in which said head portion and said supporting arms are of substantially equal length.

10. A holddown device for removably securing a cap member on the end of a tubular member comprising in integral relation an elongated head portion adapted to be disposed in the tubular member with its terminal portions in oppositely disposed openings in the wall of the tubular member; a shank portion at substantially right angles to said head portion having provision for receiving fastening means; and, a pair

of supporting arms extending from opposite sides thereof in a vertical plane at substantially right angles to said head portion, for supporting said shank portion in an upright position in the tubular member, said supporting arms also being suitably spaced from said head portion along said shank portion to permit canting of said shank portion sufficient to effect insertion of said terminal portions in said openings as aforesaid and being of a length greater than the inside diameter of the tubular member with which it is adapted to be used, whereby said device may not be passed through the tubular member.

11. A capped tube assembly comprising a tube member having oppositely disposed openings in the wall thereof; an apertured cap member at one end of said tube member; a holddown device for said cap member, said device comprising an elongated head portion disposed in said tube member with its terminal portions in said openings, a shank portion protruding through said cap member at substantially right angles to said head portion, and a pair of supporting arms integral with said shank and extending from opposite sides thereof in a vertical plane at substantially right angles to said head portion and slightly above and over the rim of the tube member; and, fastening means borne by said shank portion removably securing said cap member in position at the end of said tube member, whereby upon removing said fastening means for removing said cap, said supporting arms will contact the rim of said tube member and in cooperation with said head portion will maintain said shank portion substantially upright and maintain said holddown device in operative position during removal and replacement of said cap member.
